UNITED STATES PATENT OFFICE.

HARRY C. THAMSEN, OF HAMBURG, PENNSYLVANIA, ASSIGNOR OF TWO-THIRDS TO ALEXANDER MURDOCH, OF SAME PLACE, AND ADAM H. LEADER, OF READING, PENNSYLVANIA.

DESIGN FOR AN ATOMIZER-CASING.

SPECIFICATION forming part of Design No. 33,189, dated September 11, 1900.

Application filed April 17, 1900. Serial No. 13,274. Term of patent 7 years.

To all whom it may concern:

Be it known that I, HARRY C. THAMSEN, a subject of the Emperor of Germany, residing at Hamburg, in the county of Berks and State 5 of Pennsylvania, have invented and produced a new and original Design for an Atomizer-Casing; and I do hereby declare the following to be a full, clear, and exact description of the same, reference being had to the accompanying drawings, forming a part thereof.

This invention relates to a new and original design for atomizer-casings.

In the drawings, Figure 1 is a perspective view, Fig. 2 a plan view, and Fig. 3 a sectional view, of the atomizer-casing.

The body A is tubular in form, and the upper portion a is slightly larger in diameter

than the lower portion b, into which it merges about midway of the length. The upper portion a is provided with a circular series of 20 equidistant perforations c near the top and with an internal flange f near the point where it merges into the smaller portion b.

Having thus fully described my new and original design, what I claim, and desire to 25 secure by Letters Patent, is—

The design for an atomizer-casing substantially as shown and described.

In testimony whereof I affix my signature in presence of two witnesses.

HARRY C. THAMSEN.
